EXPANSIBLE BRACELET

Joseph J. Vastano, East Providence, R. I., assignor to Flex-Let Corporation, East Providence, R. I., a corporation of Rhode Island

Application November 25, 1949, Serial No. 6,239

Term of patent 7 years

(Cl. D45—4)

To all whom it may concern:

Be it known that I, Joseph J. Vastano, a citizen of the United States, residing at East Providence, in the county of Providence and State of Rhode Island, have invented a new, original, and ornamental Design for an Expansible Bracelet, of which the following is a specification, reference being had to the accompanying drawing, forming part thereof.

Fig. 1 is a top plan view of an expansible bracelet embodying my new design, the expansible links shown in full lines being repeated throughout the length of the bracelet as indicated by the broken lines across the center;

Fig. 2 is an edge elevation of the bracelet as shown in Fig. 1;

Fig. 3 is an enlarged perspective view of one of the top links.

The bottom links of the expansible bracelet are conventional in appearance.

I claim:

The ornamental design for an expansible bracelet, as shown and described.

JOSEPH J. VASTANO.
